FLATIRON

Walter M. Schwartz, Philadelphia, Pa., assignor
to Proctor & Schwartz, Incorporated, Philadelphia, Pa., a corporation of Pennsylvania

Application September 30, 1933, Serial No. 691,664

10 Claims. (Cl. 68—26)

This invention relates to improvements in flat irons, and more particularly in irons of the character disclosed in my copending application Serial Number 663,827, comprising adjustable means for supporting the iron in an elevated position above an underlying surface.

A principal object of the present invention is to provide an iron comprising supporting means of the character set forth, wherein the actuating means for said support is simplified and generally improved both as to operating characteristics and to arrangement in the structure of the flat iron.

More specifically, an object of the invention is to provide an iron of the character set forth, wherein the support-actuating means is directly associated with the handle of the iron.

Still another object of the invention is to provide actuating means for the support device, wherein provision is made for positive synchronization of the movement of the support elements.

The invention further resides in certain novel structural features and mechanical details hereinafter set forth and illustrated in the attached drawings, in which:

Figure 1 is a side elevation and partial sectional view illustrating an iron made in accordance with my invention;

Fig. 2 is a rear sectional elevation showing details of the iron;

Fig. 3 is a section on the line 3—3, Fig. 1;

Figs. 4, 5 and 6 are, respectively, detached views in perspective of certain of the elements of the mechanism;

Fig. 7 is a view corresponding to Fig. 1 and showing a modification within the scope of the invention;

Fig. 8 is a fragmentary elevational view showing the forward end of the handle of the embodiment shown in Fig. 7;

Fig. 9 is a sectional elevation at the rear of the iron showing the details of the operating mechanism, and

Fig. 10 is a detached view in perspective of one of the elements of the embodiment shown in the immediately preceding figures.

With reference to Figs. 1 to 6 of the drawings, the iron comprises the usual body portion 1 including the sole plate 2 and the casing 3 suitably secured to the sole plate and enclosing the heating elements. The iron further comprises a handle 4 secured to the body 1 at the top of the casing 3 in well known manner. In accordance with the principles set forth in my aforesaid copending application, the iron is provided at each side

with an arm 5 journaled for rotation in the sole plate 2, as indicated by broken lines at 6, Fig. 1, each arm projecting at the rear of the iron through a recessed opening in the lower edge of the casing 3, and thereafter extending upwardly at the rear of the casing and forwardly into recesses 7 in the sides of the casing. From this retracted position, the arms may be turned about their journal portions into positions indicated in broken lines in Figs. 1 and 2, the exposed forwardly projecting portions of the arm in this position of adjustment extending in parallel spaced relation under the sole plate 2 and constituting a suitable support whereby the iron may be maintained in an elevated position above an underlying surface. It will be noted that when the arms are in this extended or operative position and as shown in Fig. 2, the exposed forwardly extending portions of the arms lie inwardly of vertical planes through the axes of the journaled portions of the arms whereby, as long as the weight of the iron rests upon the arms, there is no tendency for the latter to return towards their normally retracted positions.

In accordance with the present invention, each of the arms 5 is provided on its journaled portion with a pinion 8, and these pinions mesh respectively with segmental gears 9, 9, which are journaled in the present instance on studs 10 projecting from a plate 11 secured to the sole plate. The opposite sides of the segmental gears 9 intermesh and establish a positive connection between the arms 5 insuring simultaneous and completely synchronized movements of the latter. Each of the segmental gears carries a rearwardly projecting screw 12, which screws pass through slots 13 in the outer ends of the transverse arm of an inverted T-rod 14, see Fig. 6, and thereby operatively connect this rod 14 with the said gears. The upwardly projecting arm of the rod 14, as shown in Fig. 1, extends through an opening in the rear upper side of the casing 3 and through the sub-casing 15 which embraces the upper ends of the terminal rods 16, 16, of the electrical heating coils, and connects at its upper end with a lever arm 17 which, as shown in Fig. 1, projects from the rear end of the hollow handle 4. The lever 17 is pivotally attached to the handle at 18 and is pivotally connected at its forward end to a bell crank lever 19. This lever 19 is pivoted at 20 to the handle and projects upwardly through a slot in the top of the handle, as shown in Fig. 1. As shown in Fig. 4, the lever 19 has on the upwardly projecting end an enlargement 21 affording a thumb rest facilitating actuation of the

lever while gripping the handle 4. A spring 22 is secured at the rear end of the lever 17, or to the upper end of the rod 14, and also to the sub-casing 15, and tends to hold the said lever 17 in the position in which it is shown in Fig. 1. In this position, it will be noted that the actuating lever 19 is in an advanced position, while the arms 5 are in the elevated or inoperative positions at the sides of the casing 3. Pivotal movement of the lever 19 in a clockwise direction, reference being had to Fig. 1, under pressure of the thumb or finger, causes an elevation of the rear end of the lever 17 and of the rod 14 and a corresponding upward oscillation of the outer segments of the segmental gears 9. This in turn results in a counterclockwise rotation of the pinions 8, see Fig. 2, and a corresponding oscillation of the arms 5, bringing the latter into the operative positions underlying the sole plate 2. When, in this position, the weight of the iron is permitted to come upon the supporting rods 5, the latter are retained by this weight in the operative position and the iron is supported stably in a normal substantially horizontal position, as shown. When the iron is elevated, however, the release of the weight of the iron from the rods 5 permits the spring 22 to act immediately to return the arms to their normally retracted positions. In this position, the forwardly extending exposed portions of the rods 5 lie, as previously set forth, in the recesses 7 at the sides of the casing 3, while the portions of the arms connecting the journaled end with the forwardly extending portion occupy a position at the rear end of the iron so that the arms offer no obstruction to the normal ironing operations.

A preferred construction of the handle 4 is shown in Figs. 1 and 3. As therein illustrated, the handle comprises two elongated segmental members 23 and 24 each provided with transverse reinforcing ribs 25, which ribs are provided in their outer faces with apertured bosses 26 for reception of the pivot pins of the levers 17 and 19. In assembly, the segmental elements 23 and 24 are arranged face to face to define in effect a cylinder which is embraced by a cork or similar cylindrical outer handle member 27. The handle further comprises end members 28 and 29, which respectively embrace the ends of the elements 23 and 24 and of the outer cylinder 27 and which are held in position by a through bolt 30, which also constitutes a means for securing the handle to the arms 31 and 32 through which the handle is secured to the body 1 of the iron. The rod 23, as shown in Fig. 3, constitutes a spacer element for the lower edges of the elements 23 and 24 and prevents binding of these elements upon the lever 17 and the lever 19. It will be noted that the elements 23 and 24 are symmetrical as to the positions of the reinforcing ribs 25 and of the openings in these ribs which receive the lever-supporting pins so that the elements 23 and 24 are reversible or interchangeable with each other. This materially facilitates assembly and avoids the necessity for individual dies or molds.

In Figs. 7 to 10, I have illustrated a modification of my invention in which the pinions 8a, which correspond to the pinions 8 of the previously described embodiment and which are similarly attached to the support rods 5a, are engaged by the toothed portions of a duplex rack 32a slidably mounted in the body of the iron. As shown in Fig. 10, the rack 32a has in its upper 75 surface a recess 33 which receives the lower termi-

nal end of a crank arm 34 depending from the rear end of a rock shaft 35 journaled in the handle 36 of the iron. A spring 37 tends to retain the arm 34 and the rack 32a in the position shown in Fig. 9, which position corresponds to the retracted position of the iron support arms 5a, see Fig. 7. The shaft 35 can be oscillated through the medium of a short crank 38 at the forward end, see Fig. 8, which extends outwardly to a position adjoining the outer surface and forward end 10 of the handle 36 readily accessible to the thumb or finger when the hand grasps the handle 36. When pressure is applied to the outer end of the arm 38 to oscillate the arm 35 against the tension of the spring 37, the rack 32a is moved to the 15 right, Fig. 9, effecting an adjustment of the arms 5a to an operative position in which the forwardly extending exposed portions of the arms underlie the body of the iron, as previously described.

There may be other modifications without departure from the invention.

I claim:

1. A flat iron comprising a body member, a hollow handle for said member, support means for the iron adjustably mounted on said body, means operative to normally retract said support, and manual support-actuating means mounted within the handle for urging the support into operative position.

2. A flat iron comprising a body member, a hollow handle for said member, support means for the iron adjustably mounted on said body, means operative to normally retract said support, a manually-adjustable element mounted in the handle, and means for operatively connecting 35 the element and said support means whereby actuation of said element urges the support into operative position.

3. A flat iron comprising a body member, a hollow handle for said member, support means for the iron adjustably mounted on said body, means operative to normally retract said support, and actuating means for the support including a manually-adjustable element mounted in the handle and means for actuating said element to 45 urge the support into operative position.

4. A flat iron comprising a body member, a handle for said member, support means for the iron adjustably mounted on said body, means operative to normally retract said support, and 50 actuating means for the support including an element pivotally mounted in the handle and operatively connected with the support and means for pivotally moving said element to urge the support into operative position.

5. A flat iron comprising a body member, rods pivotally mounted in said body member and having portions adjustable from positions adjacent the sides of said body portion to positions underlying said body, in which latter position they 60 constitute a stable support for the iron, and means for actuating said rods including a pair of intermeshed segmental gears journaled on the iron and respectively operatively connected with said rods, and means mounted on the iron for actuating said gears.

6. A flat iron comprising a body member, rods pivotally mounted in said body member and having portions adjustable from positions adjacent the sides of said body portion to positions underlying said body, in which latter position they constitute a stable support for the iron, means for actuating said rods including a pair of intermeshed segmental gears respectively operatively connected with said rods, actuating means for 75

said gears including an element operatively connected with both gears, a handle attached to said body member, and means mounted in said handle for actuating said element.

5 7. A flat iron comprising a body member, a pair of rods journaled in said body and having portions adapted in alternative positions to lie in proximity to the sides of said casing and to underlie the body, in which latter position they 10 constitute a stable support for the iron, rod-actuating mechanism at the rear end of said body member, a member movably mounted in the handle and projecting at the rear end thereof, means at the rear end of said iron operatively 15 connecting the projecting end of said member with the rod-actuating mechanism, and means for actuating said member.

8. A flat iron comprising a body member including a sole plate and a casing secured at the 20 top of said plate, support means for said iron adjustably mounted in the body member, actuating mechanism for said support means mounted

at the rear of said body member and enclosed within said casing, an actuating element movably mounted on the handle, means at the rear of the iron operatively connecting said element with the rod-actuating mechanism, and means for actuating said element to effect a movement of said support means.

9. A flat iron comprising a body member, a handle for said member, support means for the iron adjustably mounted on said body, a rock 10 shaft journaled in the handle, means for actuating said shaft, and means for operatively connecting the shaft with said support means.

10. A flat iron comprising a body member including a sole plate and a casing secured at the 15 top of said sole plate, support means adjustably mounted on the sole plate, and actuating mechanism for said support means mounted on the iron independently of and comprising elements located within said casing.
